UNITED STATES PATENT OFFICE.

THOMAS SHAW, OF NEWARK, NEW JERSEY.

TELEGRAPH-WIRE.

SPECIFICATION forming part of Letters Patent No. 289,575, dated December 4, 1883.

Application filed September 26, 1883. (No model.)

To all whom it may concern:

Be it known that I, THOMAS SHAW, a citizen of the United States, residing at Newark, in the county of Essex and State of New Jersey, have invented certain new and useful Improvements in Telegraph-Wire; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a telegraph-wire of increased durability, tensile strength, and conductivity; and it consists in the arrangements and combinations of parts, all substantially as will be hereinafter set forth, and finally embodied in the claims.

Referring to the accompanying drawings, in which like letters of reference indicate corresponding parts in each of the figures, Figure 1 is a view of a wire in course of manufacture; Fig. 2, a completed portion, and Fig. 3 a view taken through line X.

In carrying out the invention I arrange a series of tubular sections, *a a*, upon a length of steel or other metallic wire, which tubular sections are screwed together at their extremities, forming a continuous tube, said sections being previously prepared by having a screw-thread, *c*, cut on one extremity, and the opposite extremity bored out and a female thread cut therein, all as will be understood upon reference to the figures of the drawings. The tube and wire are then together drawn through a draw-plate and the parts brought to a perfect union, the diameter of the wire being

somewhat reduced and the tubular portion considerably lengthened. Where the screw-joint was first formed, the drawing process makes such a perfect union of parts as that the metal will be practically integral, so that the strength of a single continuous tube will be gained and the joint will be perfectly impervious to moisture, thus rendering a subsequent soldering or tinning process unnecessary.

The wire as a whole, thus formed, having no longitudinal seams or joints, may be twisted without danger of exposing the corrosive metal within, so that said wire possesses great durability, the tensile strength of the steel not being diminished by rust or the conductivity of the copper reduced or impaired.

Having thus described my invention, what I claim as new is—

1. The telegraph-wire composed of a core-wire, *b*, and a series of tubular sections, *a a*, secured together at their extremities and drawn into one continuous tube, substantially as set forth.

2. A telegraph-wire composed of a core-wire and a series of tubular sections having screw-threads cut on their extremities, and connected together to form a continuous covering for said core-wire, all substantially as herein set forth and shown.

In testimony that I claim the foregoing I have hereunto set my hand this 25th day of September, 1883.

THOMAS SHAW.
